UNITED STATES PATENT OFFICE.

JOHN MARION LOVETT, OF BAINBRIDGE, GEORGIA.

REIN-HOLD.

1,256,027.

Specification of Letters Patent. Patented Feb. 12, 1918.

Application filed August 8, 1917. Serial No. 185,191.

To all whom it may concern:

Be it known that I, JOHN M. LOVETT, a citizen of the United States, residing at Bainbridge, in the county of Decatur and 5 State of Georgia, have invented certain new and useful Improvements in Rein-Holds, of which the following is a specification, reference being had to the accompanying drawings.

10 This invention relates to certain improvements in rein-holds and it is an object of the invention to provide a novel and improved device of this general character whereby a rein may be supported from a 15 trace chain or the like.

The invention consists in the details of construction and in the combination and arrangement of the several parts of my improved rein-hold wherein certain important 20 advantages are attained and the device rendered simpler, less expensive and otherwise more convenient and advantageous for use, as will be hereinafter more fully set forth.

The novel features of my invention will 25 hereinafter be definitely claimed.

In order that my invention may be the better understood I will now proceed to describe the same with reference to the accompanying drawings wherein:

30 Figure 1 is a fragmentary view in elevation illustrating a rein-hold constructed in accordance with an embodiment of my invention and in applied position;

Fig. 2 is an enlarged view partly in elevation and partly in section illustrating in detail certain features of my improved device as herein embodied; and

Fig. 3 is a longitudinal sectional view taken through the device as herein embodied.

40 As disclosed in the accompanying drawings T denotes a trace chain as generally employed in connection with a plow or the like and R denotes a rein or plow line of a conventional type. While in practice a 45 plurality of my improved holds are employed I herein disclose but one of the devices as this is believed to be sufficient for the purposes of disclosure.

As herein embodied my improved rein- 50 hold embodies two elongated plates A and B arranged in predetermined spaced relation and disposed substantially in parallelism with the plate A of a length greater than the length of the plate B but having correspond- 55 ing or lower ends thereof flush. The plates A are maintained in their predetermined

spaced relation through the medium of the rivets 1 or the like and which rivets serve as shafts for the grooved pulleys 2 also positioned between the plates A and B and 60 between which the rein or plow line R is adapted to be directed as is particularly illustrated in Fig. 1 of the accompanying drawings.

The upper end portion of the plate B is 65 bent slightly inward as indicated at 3 while the upper end portion of the plate A is returned upon itself as indicated at 4 with the free terminal portion thereof terminating below the portion 3 of the plate B. The 70 free terminal of the returned portion 4 of the plate A and the inwardly bent portion 3 of the plate B afford a restricted throat between which a side bar of a link L embodied in the trace chain is adapted to be 75 passed so that a rein-hold is supported by said chain L through the medium of the hook member as afforded by the returned portion 4.

My invention is particularly advantageous 80 for use in connection with plow lines or the like as the device serves effectually to prevent the rein or line from rubbing against the animal. The improved device also serves to prolong the life of the rein or line as the 85 rollers 2 serve as anti-friction members.

From the foregoing description, it is thought to be obvious that a rein-hold constructed in accordance with my invention is particularly well adapted for use by reason 90 of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

In combination with a harness trace chain for plows or the like, a rein-hold embodying two elongated plates substantially in 105 parallelism and in predetermined spaced relation and separated one from the other throughout their lengths with corresponding lower ends substantially flush, rivets connecting said plates and maintaining the same 110 in assembled relation, said rivets being spaced longitudinally of the plates, grooved

rollers mounted upon the rivets between the plates and between which a rein is adapted to be loosely directed, the upper end portion of one of the plates being bent slightly inward, the adjacent end portion of the second plate being returned with its free end portion overlying the inwardly bent portion of the first named plate and co-acting therewith to afford a restricted entrance opening,

said returned portion of the second named plate being loosely engaged with a link of the trace chain.

In testimony whereof I hereunto affix my signature in the presence of two witnesses.

JOHN MARION LOVETT.

Witnesses:

D. R. BRYAN,
S. W. MARTIN.
